UNITED STATES PATENT OFFICE.

EDWARD S. PIPER, OF TORONTO, ONTARIO, CANADA.

SIGNAL-LAMP.

SPECIFICATION forming part of Letters Patent No. 276,278, dated April 24, 1883.

Application filed October 26, 1882. (No model.)

To all whom it may concern:

Be it known that I, EDWARD SPENCER PIPER, a subject of the Queen of Great Britain, residing at the city of Toronto, in the county 5 of York, in the Province of Ontario, Dominion of Canada, have invented certain new and useful Improvements in Signal-Lamps, of which the following is a specification.

The object of the invention is to utilize the 10 light of a railway-car, a locomotive head-light, or any other artificially-lighted chamber, for the purpose of illuminating thereby a lens or other glass used for signal purposes; and it 15 consists in the peculiar construction and arrangements of parts, as hereinafter more fully described and claimed.

Figure 1 is a perspective view of the case or box provided with two lenses or signal-glasses, situated opposite to each other, and separated 20 by a partition formed by a reflector extending obliquely from the side of each glass toward the center and open side of the box. Fig. 2 shows the application of my signaling-lamp to a caboose of a railway-car. Fig. 3 shows 25 a perspective view of the case with a single lens.

In the drawings, A is a case having flanges a, made of wood, metal, or any suitable material, shaped in accordance with any design 30 desired, and made any size most suitable for the particular position the specific case or box is intended to occupy.

B is the lens or signal-glass, which, when applied to a box made as shown in Fig. 1, is 35 duplicated, one being placed at each end of the box, immediately opposite to each other.

C is a reflector, extending obliquely from the side of each lens B toward the center and open side of the box, thereby forming two distinct compartments within the case A, each compartment being backed by a reflector, so arranged that the light admitted through the open side of the case shall be refracted onto the lens inserted into and communicating with 45 the particular compartment so formed. It will thus be seen that the reflector C not only reflects light upon the particular lens behind which it is placed, but it also serves as a partition to separate the two lenses, so that the 50 light cast on it cannot blend or interfere with the light cast onto the other. I may further

mention here that angular reflectors so arranged are specially serviceable for reflecting light admitted through the open side of the box onto the lens situated at its end, and that 55 by placing a piece of colored glass over the compartment D the rays of light admitted therein and refracted through its lens shall be colored, while the rays of light transmitted from the same source, but admitted into the 60 compartment E without passing through colored glass, will transmit from the lens applied to the compartment E a signal different from that transmitted by the lens applied to the compartment D. I may further mention that 65 a piece of tin or other blank may be similarly applied for the purpose of shutting off the light from either of the compartments, thereby blinding one signal-lens, while the other continues to cast the light intended for its particular 70 signal.

A casing thus constructed is particularly applicable to a caboose, street, or other car where a signal or tail lamp is required. In such an application an aperture is cut in the 75 side of the car, preferably in proximity to the ordinary lamp for lighting the car, which lamp sheds its light on the reflectors C, arranged as specified, which reflectors, in their turn, reflect the light thus obtained onto the lenses situated opposite to each other and suitably colored, so that the one visible from the rear of the car shall cast a danger-signal, while the white rays of light thrown from the opposite lens shall signal to the engine-man that his 80 tail signal lamp is in order. Of course, when colored glasses are applied upon the open side of the box A, as hereinbefore explained, both lenses should be made of clear glass, and the nature of the signal altered by changing the 85 colors of the glasses covering the open side of the box.

There are various ways for connecting the case A in position. It may be so formed as to fit into the window-sash. It may be permanently 95 secured by screws passing through the flanges a to the outside of the car, opposite to an aperture made through the car, for the purpose of admitting light into the box or chamber; or it may be adjustably held opposite to the 100 said aperture, so that it can be removed at will. It is therefore not necessary to detail

any particular manner of connecting it in position. When applied to a cab of a locomotive, I prefer locating it in such a position that the lamp used for making the water-gage visible shall be utilized for illuminating the interior of the box; but it will of course be understood that I do not limit myself to any particular location or to any manner of applying it in position, the sole object being to provide means for utilizing for signaling purposes the light commonly employed for illuminating any particular compartment.

Importance is attached to the fact that the device may readily be applied to street or other cars now in use by simply cutting an aperture in the side of the car corresponding to the size of the open side of the box A, and securing the box to the car, thereby utilizing the light used for lighting the car to cast a signal in either or both of two directions parallel with the travel of the car.

I am aware that colored lenses have been placed in locomotive head-lights, and reflectors have been used to throw different-colored signals through such lenses; but no such construction is sought to be covered in this application.

I do not claim, broadly, the use of a reflector and lens or signal-glass to be attached to a lamp to divert part of its light, as I am aware that such have been used before; but

What I do claim is—

1. The combination, with a car lighted by a lamp inside thereof, and having an aperture

through which shines the light from said lamp, 35 of a signal device independent of the lamp, consisting of the case A, provided with flanges a, for attachment to the side of the car, the glass B, and the reflector C, the latter arranged with one end close to the opening in 40 the car, adapting it to receive the rays of light direct from the lamp and deflect them in a direct horizontal plane through the signal-glass, as set forth.

2. A casing, A, open at one side, and provided 45 at opposite ends with glasses B, and a double reflector, C, arranged opposite the open side of the casing and adapted to divide the rays of light passing through said opening and reflect them through the glasses at the ends of 50 the case, substantially as described.

3. In a box or case having two lenses or signal-glasses inserted in it opposite to each other, and a reflector extending obliquely from the side of each glass toward the center and open side of 55 the box for the purpose of forming a partition between, and a separate reflector for each glass, the combination of colored glass so placed over the open side of the box that the rays of light admitted therethrough shall be differently colored for each compartment formed within the box by the partition, as specified, so that the light from each lens shall be of a different color.

EDWARD S. PIPER.
